UNITED STATES PATENT OFFICE.

GUS F. ROBERTS, OF FRIES, VIRGINIA.

CLEANER FOR SPINNING-MACHINES.

1,252,180.

Specification of Letters Patent.

Patented Jan. 1, 1918.

Application filed August 16, 1915. Serial No. 45,753.

To all whom it may concern:

Be it known that I, Gus F. ROBERTS, a citizen of the United States, residing in Fries, in the county of Grayson and State 5 of Virginia, have invented certain new and useful Improvements in Cleaners for Spinning-Machines, of which the following is a specification.

This invention relates to cleaners for spinning machines of the kind shown in my 10 U. S. Patent No. 1,129,312 of February 23, 1915, and the object of my present invention is to improve certain hereinafter described parts of said cleaner and its actuating 15 mechanism.

The cleaner shown in my said patent comprises endless cords, traveling in one direction only and carrying wipers which traverse the thread-boards, roller-beams, back- 20 boards and creels of the spinning frame and detach lint and other foreign matter therefrom. Each cord is guided by suitable pulleys and is weighted with a uniform tension to keep it straight and to cause it to move 25 with uniformity in one direction in a fixed path. The wipers or brushes remove the lint, etc., from the spinning frame, which lint adheres not only to the wipers and brushes but also to the cords and in order to 30 clear the wipers and cords from lint, etc., adhering thereto brushes are provided which engage the cords and wipers and detach the lint, etc., therefrom.

In my patented cleaner the cords extend 35 over one end of the frame and the weights are applied to vertical portions of the cords and the cords are driven by pulleys mounted on a shaft actuated from the main shaft of the machine which pulleys are arranged be- 40 low the plane of the thread-boards, roller-beams and back-boards, and loops are formed in the cords which extend downwardly around the driving pulleys and also across guide pulleys.

I have found that where a large number 45 of pulleys are employed to guide and drive the cords considerable wear is produced which lessens the life of the cords and according to my present invention I provide 50 means whereby the number of guide-pulleys may be reduced and the driving mechanism much simplified. I have also so organized the cleaner that the cords may be shifted to one side when the thread-boards are raised 55 during doffing or at other times. In order to prevent the cord-weights or tension de-

vices from swinging or moving out of proper operative position I have provided guides for the weights which, while permitting them to move vertically, hold them against 60 any swinging movement and I have provided means for holding the cords and their wipers in close contact with the brushes so that lint, etc., may be effectually removed.

As stated in my patent above mentioned 65 the cleaning cord is preferably made of cotton and preferably the cord consists of two strands of cotton twisted together. The wipers are preferably made of pieces of cloth such as flannel and I have found that 70 where metallic fastenings are used to attach the wipers to the cord the thread-boards, etc., are considerably worn by such metallic fastenings. In order to overcome this I attach the wipers to the cords by untwisting 75 the strands sufficiently to permit the wipers to be passed between them and then again twisting the strands to tightly hold the wipers. This I find to be a secure way of attaching the wipers to the cords and no 80 other fastening device is necessary, although preferably the leading edge of the wiper is attached to the cord by a single stitch.

Other features of my invention will be 85 hereinafter described.

In the accompanying drawings,

Figure 1 is a perspective view with parts broken away of a part of a spinning machine with my improvements applied.

Fig. 2 is a detail view on an enlarged 90 scale and in perspective showing how the wipers are attached to the cords.

Fig. 3 shows an elevation of one end of the spinning machine with my improvements applied.

Fig. 4 is a detail view on an enlarged scale and mainly in section and with parts broken away showing how the cleaning cord for one of the thread-boards, roller-beams and back-boards is supported and driven.

Fig. 5 is a plan view of the parts shown in Fig. 4.

Fig. 6 shows a section of the same.

Fig. 7 is a detail view in section showing how the cleaner for the creel is supported 105 and driven at one end; and

Fig. 8 is a plan view of the parts shown in Fig. 7.

Fig. 9 is a detail view in vertical section of one of the weighted pulleys and its guide.

Fig. 10 is a similar view taken at right angles to that of Fig. 9.

Fig. 11 is a detail view of a part of one of the weights.

While my improvements are especially intended for use in spinning machines, they 5 may of course be applied to other similar machines. Only such parts of the machine as are necessary to illustrate my invention are shown, and in the drawings B, B' indicate the thread-boards, B² the roller-beams, 10 B³ the back-boards and C the creel. The drawing rolls are indicated at D, the roving bobbins at E and the spindles, which receive the threads from the drawing rolls, at F, Fig. 3.

15 Each of the thread-boards is provided with a cleaner consisting of an endless cord G which extends around a pulley g at one end of the frame which spreads the cord into two parallel members, and at the other 20 end of the frame the cord extends over pulleys g' and from thence downwardly across the end of the frame where the loop formed thereby supports a weighted pulley H. As usual, each thread-board B is hinged to a 25 roller-beam B², as indicated at b, and while the pulley g normally overlaps the thread-board provision is made, as will be herein-after described, for moving the pulley laterally away from the thread-board so that the 30 latter may be lifted during doffing and at other times.

The cord G carries wipers or cleaners x which are held close to the thread-board by 35 the cord and operate to clean this board as well as the roller-beam and back-board. Each of the thread-boards and its associated roller-beam and back-board is provided with a cleaner, as indicated in Fig. 1, and the creel C is provided with a similar cleaner. 40 The cord I for the creel passes around a pulley I' at one end of the frame and over pulleys i at the opposite end of the frame. These guide pulleys are arranged to properly spread the cord and from the pulleys i 45 the loop of the cord extends downwardly over a weighted pulley J.

Experience has demonstrated that the weighted pulleys shown in my prior patent often swing laterally to such an extent as 50 to interfere with the efficient operation of the cleaner and to overcome this I have provided guides which, while permitting the pulleys to move vertically to the required extent to compensate for the lengthening 55 and shortening of the cords due to atmospheric changes, prevent any lateral movement thereof. Instead of suspending the weights from the pulleys as before, I now provide for each pulley a bifurcated weight 60 H² which straddles the pulley and engages the axle thereof. Each leg of the bifurcated weight is formed with a vertical slot h² which receives a bearing block h³ in which the axle h⁴ of the pulley rests. Each 65 weighted pulley enters a guide box H³

which may be bolted to the factory floor, or may be supported by a frame H⁴ (Fig. 1) bolted to the end frame of the machine. Each guide box is provided with a stop H⁵ which limits the upward movement of the 70 weight. The guide boxes may be made in various ways but are preferably so constructed that the pulleys extend through vertical slots h⁵ in the opposite sides of the box. 75

I do not limit myself to the particular form of weight guides shown as the same result may be accomplished by other means.

Rotary brushes M, M', are mounted to 80 rotate on one of the end frames and to engage the vertical portions of the cords G and I. These brushes may be driven in any suitable way, preferably by means of belt gearing N driven from a pulley n on a shaft O which shaft may be driven in any suitable way. 85

In order to hold the wipers in close contact with the brushes I provide the guards M² which may be attached to the frame in any suitable way close to the brushes M. 90 No such guard is required for the brush M' inasmuch as it is located close to the brushes M, M' and the cord I passes between these brushes which serve to remove all lint from the wipers. 95

As shown in Fig. 2 the wipers are attached to the cord without the use of metallic fastenings. The cord employed preferably consists of two strands, and in order to attach a wiper the strands are untwisted sufficiently 100 to allow the wiper to be passed through between the strands then the strands are again twisted, as shown in Fig. 2, and this serves to securely attach the wiper to the cord. For additional security however I may attach the front or leading end of the wiper to the cord by a single thread or stitch X' 105 as shown in order to prevent the leading end of the wiper from piling up or slipping back and thus forming a lump or knot which 110 would prevent a proper drawing contact with the driving pulley. 115

As before stated each thread-board is hinged to its adjacent roller-beam and as it is desirable that one side of the cord should 120 overlap the thread-board while the other side overlaps the back-board, it is desirable to provide some means by which each guide pulley g may be moved to one side when it is necessary to raise the thread-board. I accomplish this by passing the pivot K of the pulley g through a slot in the roller-beam and through the arm k of a bracket K' which is connected by a threaded stud k' to an adjustable vertically arranged bracket K² attached to one of the end pieces A of the machine frame. Devices k² are employed for adjusting the bracket K² vertically, and the connection between the brackets K' and K² is such that the bracket K' may be turned 125 130

to a limited extent in such manner as to move the pulley g laterally away from the thread-board in the manner indicated in Fig. 5. The pivot K carries a beveled pinion l meshing with a beveled pinion l' on a shaft L mounted in bearings in the bracket K' and this shaft carries a sprocket wheel l^2 connected by a chain l^3 with a sprocket wheel l^4 on a shaft O which in practice is the front 10 fluted steel drawing roll which drives the back and top rolls of the set of drawing rolls. The shaft O carries a spur-wheel o geared by the train of wheels $o', o^2, o^3, o^4, o^5, o^6$ to the shaft P which is the driving shaft 15 of the machine and on which is mounted the band cylinder P' extending along the whole length of the frame by which the spindles F (Fig. 3) on both sides of the frame are driven through the bands p . The shaft L 20 on the opposite side of the machine is in like manner driven by a sprocket chain Q through the gearing shown which is of usual construction and need not be described in detail further than to say that the shaft q 25 is the front fluted steel drawing roll which drives the back and top rolls on that side of the machine where it is located. The construction is such that the pulleys g are rotated at the proper speed to drive the 30 cleaning cords when the thread-boards are lowered or when the machine is in operation. When it is desired to raise the thread-boards the brackets K' may be turned in the manner indicated in Fig. 5 so that the pulleys and 35 cords are out of the way of the thread-boards. In practice, however, each cord and pulley will automatically swing into or assume the position shown in Fig. 5 as the lower or outer edge of the pulley comes in 40 contact with the thread-board while the latter is being raised. When the thread-board is released or lowered the cord and pulley will be automatically brought back to working positions by reason of the fact that the 45 cord is held at all times under tension by its weight. In order to support the inner ends of the brackets K' at the desired elevation I provide lifting devices R each comprising a stem r which is threaded and carries nuts r' 50 which may be adjusted to hold the bracket K' and consequently the pulley g in the desired plane.

The pulley l' which guides and drives the cleaning cord I for the creel is secured to a 55 vertical shaft s mounted to turn in a bracket S adjustably secured to the end frame piece A. The lower end of the shaft carries a beveled pinion s' meshing with a corresponding pinion s^2 on a horizontal shaft S' mounted 60 to turn in bearings in the bracket S and carrying outside the frame piece A a sprocket wheel T connected by a chain t with a sprocket wheel t' on a stud U carrying a spur or intermediate gear V meshing 65 with the wheels Q' and o' . In this way the

pulley and the cord I are driven from one of the intermediate gears of the train of gears in the front drawing roll drive.

By my present improvements the devices for cleaning the cords and wipers is made 70 more efficient inasmuch as the cords and wipers are held close to the brushes and the weighted pulleys are prevented from swinging away from the brushes. The thread-boards can be very easily raised during 75 doffing and at other times, it being only necessary to move the pulleys g sidewise and inward to a small extent so that they with the outer sides of the cords are moved out of the way of the thread-boards. Furthermore, 80 the pulley g and the cord G are so arranged that they may be moved sidewise and inward automatically in the manner before described. These pulleys g constitute guides for the cords and also drivers therefor and 85 receive motion from the usual mechanism employed for driving the drawing rolls. By comparing my present improvements with the mechanism shown in my before mentioned patent it will be seen that the driving 90 mechanism is much simplified and many of the guide pulleys shown in said patent are dispensed with so that the wear on the cords is materially reduced and their life greatly prolonged. 95

I claim as my invention:

1. The combination with the machine frame, of an endless cleaning cord traversing the frame carrying laterally projecting wipers and having a vertically disposed portion 100 at one end of the frame, a brush mounted on one end of the frame for cleaning the wipers on the vertically disposed portion of the cord, and a shield for holding the wipers in engagement with the brush. 105

2. The combination with the machine frame of the thread-board, the roller-beam, the drawing-rolls, gearing for driving the drawing rolls, an endless cleaning cord traversing the thread-board and roller-beam, 110 a horizontally arranged pulley for guiding and driving the cord the axis of which extends through the roller-beam and the edge of which overlies the thread-board and holds one side of the endless cord over the thread-board, a support for said pulley mounted to turn about a vertical axis for moving the pulley sidewise, and gearing arranged below the roller-beam and which is connected with the drawing-roll driving mechanism 115 for actuating said pulley. 120

3. The combination with the machine frame and its thread-board of an endless cleaning cord traversing the frame, a pulley for the cord overlying the thread-board, 125 and a support for said pulley which is shiftable sidewise for moving the pulley out of the way of the thread-board when the latter is raised.

4. The combination with the machine 130

frame of a thread-board hinged to the frame and mounted to swing upward, an endwise movable cleaning cord traversing the thread-board, a guiding and driving pulley having 5 a portion overlying the thread-board, a support for said pulley mounted to swing about a vertical axis, and means for rotating the pulley.

5. A spinning or like machine equipped 10 with a cleaner comprising an endless cord placed under tension, a combined driving and guiding pulley for the cord, a support or mounting for said driving pulley which is adapted to swing horizontally at times 15 with said pulley, and driving mechanism for said pulley a part of which swings with it when said mounting is swung.

6. The combination with the roller-beam, 20 and the thread-board, of an endless cleaning cord traversing the roller-beam and the thread-board, and a pulley for the cord mounted on the roller-beam, overlying the joint between the thread-board and roller-beam and mounted to swing horizontally 25 over the roller-beam away from the thread-board.

7. The combination of the roller-beam, a 30 thread-board hinged to the roller-beam, a cleaning cord traversing the thread-board and the roller-beam, a driving pulley for the cord overlying the thread-board, driving means for the pulley, and a mounting for the pulley supporting part of said driving

mechanism and which is adapted to swing 35 sidewise with the pulley away from the plane of the thread-board to allow the latter to be raised.

8. The combination with the roller-beam, back-board and hinged thread-board of a spinning machine, of an endless cleaning 40 cord therefor, a horizontally arranged pulley for guiding the cord at one end of the machine and for holding parallel portions of the cord over the back-board and thread-board, driving mechanism for said pulley, 45 and a swinging bracket which supports the pulley and permits it to move sidewise away from the thread-board.

9. The combination with the roller-beam, back-board and hinged thread-board of a 50 spinning machine, of an endless cleaning cord therefor, a horizontally arranged pulley for guiding the cord at one end of the machine and for holding parallel portions of the cord over the back-board and thread- 55 board, driving mechanism for said pulley, a swinging bracket which supports the pulley and permits of its being moved sidewise away from the thread-board, and means for adjusting said bracket vertically. 60

In testimony whereof, I have hereunto subscribed my name.

GUS F. ROBERTS.
